UNITED STATES PATENT OFFICE.

MARCUS MAX UHLIG, OF ERDMANNSDORF, GERMANY.

APPARATUS FOR APPLYING WADDING TO PAPER.

SPECIFICATION forming part of Letters Patent No. 625,430, dated May 23, 1899.

Application filed August 4, 1898. Serial No. 687,745. (No model.)

To all whom it may concern:

Be it known that I, MARCUS MAX UHLIG, a subject of the Emperor of Germany, residing at Erdmannsdorf, Empire of Germany, 5 have invented a certain new and useful Apparatus for Applying Wadding to Paper, of which the following is a full, clear, and exact description.

The present invention relates to an apparatus for applying medicinal wadding to closet and other paper.

In order to render the present specification more easily intelligible, reference is had to the accompanying drawings, in which similar letters of reference denote similar parts throughout both views.

Figure 1 is a side elevation, and Fig. 2 a plan, of one form of machine for carrying the invention into practice.

20 A pair of levers *a*, having two sets of bearing-arms, are pivotally mounted on the shaft *b* at the lower part of the machine-frame. The paper-roll *i* is revolvably supported in forks supported on the front part of the machine-frame, while the drum or reel *c* for the finished ware is supported in the forward upwardly-extending bifurcated arms of the levers *a*. A guide-drum *k* is mounted in the machine-frame, on which drum the said reel *c* runs by friction. 25 The fleece coming from the carding-engine is gathered and fed to the paper by means of a partly-open guide funnel or plate *m* and passes thence under a pressure and guide roll *d*, mounted in the rear part of the arms *a*, onto the paper. A milk-trough *e* is mounted at the rear part of the machine-frame to swing on pivots *f*, said trough having upwardly-extending arms, to which is pivoted a connecting-rod *h*, which 30 couples the rear end of the trough to a lever *g*, adapted to be thrown around its pivot, and thus to tip the trough, so that the cushion *f'* may be tipped away from the paper while the machine is running. The fleece coming from 35 the carding-engine passes under the comb *l* and thence to the gathering guide-plate *m*.

The operation of the apparatus takes place in the following manner: The paper from the drum *i* passes around the drum *k* and under 40 and onto the drum *c*. All these drums are supported in open bifurcations of their bearings and may be easily removed. The fleece passes

from the carding-engine at the same rate of speed as the paper is moving. The paper is coated with a thin coating of milk as it passes 55 the cushion *f'*, and the fleece coming from the guide-plate *m* passes onto the wet paper, on which it is pressed by the roll *d* and by the drum *c*, which rests with its whole weight on the drum *k*, from which it receives its motion. When the drum *c* is full, it may be lifted out of its bearings and another drum substituted.

By lifting the levers *a* the roll or drum *c* may be brought out of contact with the drum 65 *k*, and by turning the handles *g* the milk-trough may be tipped so as to move its contents away from the cushion *f'* when the machine is out of operation. The levers *a* may be tipped or swung on their pivots by means 70 of the handles *g'*.

The bridge or guard *n* serves to hold the paper off the drum *k* immediately after the wadding has been applied to the paper, so as to prevent the edges of the latter from coming 75 into contact with any moisture which may be on the drum *k* as far as possible—*i. e.*, to give the edges a short time for drying.

If desired, two or three apparatuses may be arranged side by side, as indicated by the 80 lines I, II, and III, according to the length of the carding-engine. Drum *k* may be driven by pulleys *K*.

I claim as my invention—

1. In a machine for applying wadding and 85 the like to paper continuously, the combination of a pressure-drum *d* and a reel *c* for the finished ware, a pair of levers *a* having bifurcated arms to support said drum and reel, a machine-frame, at the lower part of which 90 said levers are pivotally supported, a driving-drum *k* on which said reel *c* rests and means for rotating the same, a paper-reel and bifurcated bearings in the machine-frame to support the same, a guide-plate *m* for the fleece 95 coming from the carding-engine and passing under drum *d*, and means for supplying milk to the said paper before the fleece meets the same substantially as described.

2. The combination of a paper-reel and a 100 driving and pressure drum, a stationary machine-frame to support said reel and drum revolvably, a pair of arms *a*, pivoted to said frame and having upwardly-extending bifur-

cations, and a reel *c* for the finished ware mounted therein, a pressure-drum *d* for the fleece, a milk-trough mounted between said arms in proximity to said drum *k* and means 5 for tipping the same as specified, a suction-cushion dipping into the said milk-trough and against which the paper from the paper-reel brushes, a guide-plate *m* at the rear of the drum *d* to guide the fleece coming from

the carding-engine and means for rotating to the said drum *k* substantially as described.

In witness whereof I have hereunto set my hand in presence of two witnesses.

MARCUS MAX UHLIG.
